UNITED STATES PATENT OFFICE.

ALBERT MARLEWSKI, OF CHICAGO, ILLINOIS.

SUPPORTING BRACKET.

Application filed May 8, 1926. Serial No. 107,632.

This invention relates to a safety supporting bracket or platform for use in cleaning windows from the outside.

It is an object of this invention to provide 5 an improved bracket that can be adjusted to fit various thicknesses and constructions of window frames and can be folded up into a small compass when not in use or while being shifted from one window to another.

It is also an object of this invention to provide means for leveling the bracket when positioned on the window sill and to maintain the platform in position to insure the 15 engagement of the safety hooks over the inner edge of the sill.

Other and further important objects of this invention will be apparent from the disclosures in the specification and the accompanying drawings.

This invention (in a preferred form) is illustrated in the drawings and hereinafter more fully described.

On the drawings:

25 Figure 1 is a side elevation of a device embodying the features of the invention in plan on a window sill.

Figure 2 is a rear view thereof.

30 Figure 3 is an end fragmentary sectional view taken on the line III—III of Figure 1.

Figure 4 is an end fragmentary sectional view taken on the line IV—IV of Figure 1.

As shown on the drawings:

35 A cross section of a typical masonry wall is shown with an overhanging stone sill 10 projecting beneath the wood sill 11 of the window frame proper, an interior ornamental sill 12 having a rounded overhang 13 being

40 also indicated. The device of this invention comprises a platform and railing built up on a frame comprising parallel inverted T bars 14 resting on the ornamental sill 12 and having hooks 15 engaging over the over-

45 hang 13 thereof, wood filler blocks 16 being fitted over the upstanding edges of the bars 14 to receive the flooring 17. Angle plates 18 are fitted at the outer corners, for a purpose to be brought out later, and slant-

50 ing bars 19 are secured thereto by the brackets 20 and set screws 21, these bars carrying shoes 22 adapted to engage the corner of the stone sill. The bars 19 are adjustable to fit

various wall thicknesses and the outer ends are curved as shown to provide handles.

55 These bars maintain the hooks 15 in engagement with the overhang 13 of the ornamental sill but are not intended to carry the weight of the platform, which is borne by the adjustable screws 23 which are threaded in the brackets 24 clamped to the bottom rails of the T bars. These screws have a ball and socket engagement with feet 25 which rest on the slanting surface of the stone sill.

60 The corner brackets or angle plates 18 serve as pivots for a rod 26 on which is mounted the lower panel 27 of a railing, the upper panel 28 of which is pivoted to the upper edge of the lower panel by the 70 rod 29. Suitable pivoted stops 30 prevent relative movement of the upper panel when turned up and likewise hold the upper panel within the bounds of the lower panel when folded, the two panels together then folding down onto the platform. As shown in dotted lines, the lower ends of the lower panel are formed to prevent outward movement thereof beyond the perpendicular.

75 The side railing panels 31 are similarly 80 made in two sections folding together and in turn folding down onto the platform, the hinge 32 shown on the left in Figure 2 bringing that panel flat to the platform, while the hinge axis 33 for the right hand panel is elevated sufficiently above the platform to allow this panel to fold over the first one. Then the rear panel folds down over the two side panels.

85 The two side panels are held from outward movement past the perpendicular by the bars 34 and 35 secured to the rear panels, these bars passing down past the outside of the platform in folded position. The top bar 35 is engaged by a hinged clamp 36 95 which holds it to the top bar 37 of the upper side panel.

90 I am aware that many changes may be made, and numerous details of construction may be varied through a wide range without departing from the principles of this invention, and I therefore do not purpose 100 limiting the patent granted hereon, otherwise than necessitated by the prior art.

105 I claim as my invention.

In a device of the class described, a plat-

form, means for temporarily securing said platform in place on a window sill, skeleton railings on three sides of said platform adapted to fold down thereon, one on top of another, said railings each comprising a pair of spaced standards, a secondary panel pivoted between the upper portions of

each pair of standards and adapted to extend above or to be folded between the respective pair of standards.

10

In testimony whereof I have hereunto subscribed my name.

ALBERT MARLEWSKI.
